UNITED STATES PATENT OFFICE

104,803

DESIGN FOR A COMBINED TRUNK GUARD AND GRILLE GUARD

Louis S. Poncher, Chicago, Ill.

Application March 6, 1937, Serial No. 68,051

Term of patent 7 years

To all whom it may concern:

Be it known that I, Louis S. Poncher, a citizen of the United States, residing at Chicago, in the county of Cook and State of Illinois, have invented a new, original, and ornamental Design for Combined Trunk Guard, and Grille Guard, of which the following is a specification, reference being had to the accompanying drawing, forming a part thereof.

Fig. 1 is a front elevation of the trunk guard showing my new design.

Fig. 2 is a side view thereof.

Fig. 3 is a bottom end view thereof.

The dominant features of my design reside in the portions shown in full lines.

I claim:

The ornamental design for a combined trunk guard and grille guard substantially as shown and described.

LOUIS S. PONCHER.
